Primary Examiner — Karen S Acker(74) *Attorney, Agent, or Firm* — Stites & Harbison, PLLC; Juan Carlos A. Marquez, Esq.(57) **CLAIM**

The ornamental design for a display screen with graphical user interface for a sports device, as shown and described.

DESCRIPTION

FIG. 1 is a front view of the display screen with graphical user interface for a sports device according to the present design; and,

FIG. 2 is a front view of the design of FIG. 1 shown in an environment of use.

The broken lines in the drawings represent environmental subject matter and form no part of the claimed design.
